UNITED STATES PATENT OFFICE.

DANIEL H. NOYES, OF ATHOL, MASSACHUSETTS.

CLOTHES-DRIER ATTACHMENT FOR HOT-WATER TANKS.

Application filed April 22, 1926. Serial No. 103,687.

This invention relates to drying racks for towels, cloths and the like, and especially to that class used in household kitchens and like places.

5 It is particularly adapted to be clamped on to cylindrical objects such as boilers, and may be so adjusted as to avoid contact with walls, should the said boiler be located in close proximity thereto, or in an angle, or 10 corner of a room.

It is light, neat in appearance, and low in cost of manufacture.

Further advantages and objects will be described in detail in the following specification, and illustrated in the accompanying drawings, in which:

Fig. 1 shows the device in its simplest form mounted on a boiler of the class described; the said boiler being located in an 20 angle of an adjacent wall.

Fig. 2 shows a plan view and indicates the relative position of the rack to the adjacent angular walls.

Fig. 3 shows an enlarged view of a hook, 25 as shown in the preceding views, and a section of the retaining band.

Fig. 4 shows a modification of the device, in which a longer pin is detachably held within a slotted recess in the retaining band.

30 Fig. 5 shows a fragmentary section on the line 5—5 of Figure 4.

Fig. 6 shows a fragmentary top view of the parts illustrated in Figure 5.

The rack is comprised of the following 35 parts:

A retaining band, or strap 10 of iron, or any suitable material, is adapted to be secured to a cylindrical object such as the boiler shown at 11, by means of the binding 40 clamp 12. The band member is provided with a bead, or raised portion 13 which extends for the full length of same and near to its bottom edge; the object of this bead is to offset the tendency of the band to sag 45 forward at the top when under load; it also affords a firmer grip on the supporting object to prevent any downward slipping movement.

The hook members as shown at 14 and 15 50 are secured to the band 10 near to its upper edge and have their downturned portions resting against the surface of the said band.

In the modification as shown in Figure 4 of the drawings; hanger pins as 16, which

may be of varying lengths, are provided 55 with flange members as 17, which rest within a slotted recess as shown at 18. These hanger members may be removed and replaced at will, and long, or short ones used to meet the requirements of the moment. 60

The hooks as shown at 14 may be provided with flanged rear extremities and secured to the band in the same manner as the pins 16.

While I have shown the preferred forms 65 of my invention; I do not wish to be limited to the exact details of construction as illustrated herewith, but claim the right to such minor departures therefrom as may come within the scope of the appended 70 claims.

Having thus described my invention, what I claim as new and desire to secure by Letters Patent, is as follows:

1. In a drying rack of the class described, 75 a band adapted to be clamped upon the cylindrical surface of a cylindrical body comprising an upper offset portion and a lower portion of a diameter less than said upper offset portion adapted to engage the 80 walls of said cylindrical body, said upper offset portion being provided with open slots extending from the top thereof, and hanger pins having enlargements on the ends thereof adapted to be inserted into said slots 85 from above through the upper open end thereof to a position between the inner surface of said offset portion and the outer surface of said cylindrical body, said hanger pins being removable bodily from said band. 90

2. In a drying rack of the class described, 95 a band adapted to be clamped upon the cylindrical surface of a cylindrical body, a plurality of outwardly projecting pockets on said band having an open end at the top thereof, the front of said pockets being provided with a slot extending from the open top thereof, a hanger pin, a projection on said hanger pin spaced from the end thereof, and a lug on the end of said projection, said lug being adapted to be inserted in said 100 pocket from above through the open end thereof, said projection being confined in said slot for removably supporting said hanger pin. 105

In testimony whereof I have affixed my signature.

DANIEL H. NOYES.
